UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL-BURNER.

1,372,694.

Specification of Letters Patent. Patented Mar. 29, 1921.

Application filed August 15, 1919. Serial No. 317,670.

To all whom it may concern:

Be it known that I, RUDOLPH HOFFMAN, a citizen of the United States, residing at Kankakee, in the county of Kankakee and 5 State of Illinois, have invented certain new and useful Improvements in Oil-Burners, of which the following is a specification.

The invention relates to oil burners of the blue flame type comprising wick retaining means such as an annular burner bowl 10 or trough connected with a source of oil supply, and a pair of perforated combustion tubes connected together in concentric relation and arranged to be supported upon the 15 trough in operative association with the wick.

In the use of burners of this general character the combustion tubes are tilted from their operative position to permit of access 20 to the lighting ring. In this operation, difficulty is experienced in properly replacing the combustion tubes upon their seats on the burner bowl. The object of this invention is to provide guiding or centering means 25 for the combustion tubes, of advantageous construction, for facilitating their replacement into their proper operative positions after having been tilted or bodily lifted from their seats.

30 In the accompanying drawings wherein I have illustrated a preferred embodiment of my invention, Figure 1 is a central vertical sectional view through a burner embodying the features of my invention, the view being taken in the plane of line 1—1 of Fig. 2. Fig. 2 is a horizontal section taken on line 35 2—2 of Fig. 1. Fig. 3 is a detached elevation showing the parts of the guiding means in position to be assembled.

40 The burner as herein illustrated comprises an annular bowl or trough 1 having a wick or lighting ring 2 therein of asbestos or the like. Said trough communicates at 3 with a suitable source of oil supply (not shown). 45 4 and 5 indicate perforated combustion tubes for the burner secured together in concentric relation by any well-known means (not shown) and adapted to be seated upon the trough 1 in operative association with the 50 wick 2. To this end the upper edges of the trough 1 are provided with oppositely projecting horizontal flanges 6 and 7 formed integral with the walls of the trough. Preferably said flanges are disposed slightly below the upper edges of the trough so as to

prevent lateral movement of the combustion tubes relative thereto.

The guiding and centering means for the combustion tubes comprises a plurality of radially extending arms or wings carried by 60 the trough 1. Herein, said wings are formed by two angular members 8 and 8^a, each providing two wings disposed substantially 65 90° apart, and the wings of each member are connected together by straps 9 and 10. 70 These straps are so arranged as to interfit to form a central socket 11 for receiving a retaining pin 12, the opposite ends of which may be bent as at 13 and 14 to prevent its removal from its operative position. In 75 order that the upper end of the pin 12 shall not project upwardly above the upper edges of the wings the upper strap 10 of the wing member 8^a is notched as at 15. The upper edges of the wings are inclined downwardly 80 and outwardly and their upper outer edges are rounded as at 16 with their outer upright edges disposed a short interval inwardly of the vertical plane of the wick 2. Said upright edges of the wings thus guide 85 the inner combustion tube and thereby the outer tube connected therewith, centering the tubes relative to the trough 1 and wick 2. Notches 17 are formed in the outer edge of 90 each wing near the lower portion thereof, and the portions 18 of the wing below said notches are extended outwardly so that when the parts are in operative position the extended portions engage with the inner wall of the burner trough 1.

In assembling the guiding means, the two wing members 8 and 8^a are placed oppositely within the burner trough 1 with the outer edges of the wings engaging the inner surface of the trough and the flange 7 of the 95 trough entered in the notches 17. At their inner or central portions the members are brought together so that the straps 9 and 10 interfit to form the socket 11, and the pin 12 is inserted into the socket and its ends 100 bent to lock the parts in position. The parts are so proportioned and arranged that when in operative position the wing members interengage and abut the trough 1 whereby relative movement and play between the parts is prevented and the wings 105 are held spaced apart in substantially equidistant relation.

It will be seen that I have provided a burner with guiding means for the combus- 110

tion tubes of an advantageous character. The paucity and simplicity of the parts lends cheapness to the device, it does not interfere with the operation of the burner, 5 and may be readily assembled or disassembled when desired.

I claim as my invention:

1. An oil burner comprising, in combination, wick retaining means having an annular flange, a combustion tube arranged to be seated upon said flange, two pairs of wings, each pair connected by one or more straps adapted to interfit to form a central socket, and a pin entered into said socket to 10 secure the wings together, the outer edges of said wings detachably engaging and supporting said wings upon said wick retaining means, said wings being adapted to guide said combustion tube toward and from its seat.
2. An oil burner comprising, in combination with a combustion tube and a seat therefor, means for guiding the tube to a position upon its seat comprising a plurality of wings spaced apart and connected together, 25 at their inner edges with their outer edges operatively engaging said seat so as to restrain upward and downward movement of said wings.
3. The combination with a pair of combustion tubes and horizontal flanges forming supports therefor, of means for guiding the combustion tubes into position upon their seats comprising two angular members each 30 providing a pair of wings and detachably connected together at the inner edges of the wings and to one of said flanges at the outer edges of the wings.
4. In an oil burner, in combination with a 40 combustion tube and an annular seat therefor, of means for guiding the combustion tube toward and from its operative position upon said seat comprising a plurality of wings, and means at the inner edges of said wings securing them together in spaced relation, the outer edges of said wings being notched to receive said annular seat member and secure said wings against upward or 45 downward movement.
5. In an oil burner, the combination with a 50 combustion tube and an annular seat mem-

ber therefor, of means for guiding the combustion tube vertically relative to said seat member comprising a plurality of members providing a plurality of wings the outer edges of which are adapted to operatively engage and support said wing members upon said seat member, and means for securing the inner portions of said wing members together. 60

6. In an oil burner, the combination with annular wick-retaining means and a combustion tube arranged to be supported thereby, of means for guiding the combustion tube relative to the wick comprising a plurality of radially extending members supported against removal by the wick-retaining means and having guiding edges for centering the lower end of the combustion tube relative to said wick-retaining means. 65

7. In an oil burner, the combination with wick-retaining means and a combustion tube supported in operative association with the wick of means for guiding the combustion tube relative to its support comprising a plurality of upright members secured to the wick-retaining means and having upright guiding edges located adjacent the vertical inner periphery of the wick. 70

8. The combination with a pair of combustion tubes and horizontal annular flanges forming supports therefor, of means for guiding the combustion tubes into position upon their seats comprising two angular members each having a pair of wings and connected at their angular portions by a pintle, said wings having notches in their outer edges to receive the supporting flange for the inner combustion tube. 80

9. In an oil burner, the combination with a tiltable combustion tube and an annular seat member therefor, of means for guiding the combustion tube in seating it on said seat member comprising a plurality of angularly arranged pairs of wing members connected at their angular portions by a pintle and secured to said seat member, said wings having curved edges adapted to engage and guide said tube to its seat. 90

In testimony whereof, I have hereunto set my hand.

RUDOLPH HOFFMAN.
